CIRCUIT MAKER AND BREAKER

Carl J. Anderson, Chicago, Ill., assignor to C. J. Anderson & Company, Chicago, Ill., a corporation of Illinois

Application September 18, 1931, Serial No. 563,577

10 Claims. (Cl. 200—18)

The present invention relates in general to electrical circuit makers and breakers and more particularly to a special form of this device, primarily adapted for the switching of electrical circuits to control electrical equipment.

One of the objects of the present invention is to provide an improved switching device which may be employed to control a plurality of circuits.

Another object is to provide a device of this character which is compact, easily manufactured and which may be controlled from a drum or cam of a floor selector, or other controlling device in an electrical control system.

Another object is to provide a switching device of this character which is particularly adapted to simplify the electrical circuits and equipment in an elevator signalling and control system.

Another object is to provide a switching device of this character which may be readily adapted to control and increase the number of circuits, depending upon the type of electrical control system employed.

A further object is to provide a device of this character which may be easily maintained, compactly mounted, and positively operated.

Still another object is to provide an improved switching device that will reduce the number of controlling relays ordinarily necessary in an electrical control system.

30 There are other objects of my invention which, together with the foregoing, will be described in the detailed specification that is to follow, taken in conjunction with the accompanying drawings forming a part thereof.

35 The present invention is particularly adapted to co-operate with the electrical control system disclosed in the co-pending application of John Podosin, Serial No. 440,044, filed March 29, 1930. This application discloses the functioning of my 40 improved switching device in conjunction with an electrical elevator control system, and discloses the manner in which its use simplifies the control circuits, and reference is hereby made to that application.

45 In elevator control systems with which my improved switching device is adapted to function, in addition to the usual hoisting equipment, electrical circuits and control equipment are provided for the purpose of controlling the elevator.

50 Signalling devices and control circuits are also employed for indicating the travel of an elevator to waiting passengers, and either to control the elevator automatically or indicate the desire of the passenger to the elevator operator. In order 55 to bring about proper functioning of these sig-

nalling and control circuits, it is customary to provide an electrical switching device, designated in this class of work as a "floor selector", driven from the hoisting equipment in such manner as to have a particular position for each floor in the 60 building that the elevator is designed to stop at. The number of circuits controlled by these floor selectors depends upon the number of floors in the building and also upon the type of hoisting equipment. The number of speeds that the 65 hoisting equipment is capable of is another governing factor.

My improved switching device may be readily employed to meet the requirements mentioned and, as before stated, reduce the complexity of 70 electrical controlling signalling circuits ordinarily required.

Referring now to the drawings:

Fig. 1 is a plan of my improved floor selecting device adapted for a single speed elevator control system in a building in which the elevator is required to stop at three landings;

Fig. 2 is a sectional elevation of the same taken along the line 2—2 of Fig. 1;

Fig. 3 is a partial plan of a slightly modified 80 form of selecting device for a two-speed elevator installation;

Fig. 4 is a side elevation of the same;

Fig. 5 is a detailed plan of the contact structure employed in my improved switching device; 85 and

Fig. 6 is a medial cross section thereof taken along the line 6—6 of Fig. 5.

It will, of course, be obvious that while I have stated my improved switching device is adapted 90 to function with the electrical control equipment of the above cited co-pending application of John Podosin, that this is merely by way of illustration and that my improved switching device is capable of wide, general use. While I have shown 95 the device in the drawings and so described it in connection with an elevator control system employing a floor selector, it is capable of wide, general application and may be employed 100 wherever drum controllers or cam operated switches are necessary, as well as in other places which will suggest themselves to those skilled in the art.

In the drawings, like reference characters apply to similar parts throughout.

While I have illustrated in Fig. 1 a plurality of my improved switching devices and a plurality of cams mounted upon a single shaft, it will be understood that this is a mere adaptation of my 110

invention to a floor selector, as in a single speed elevator control system for three landings.

My improved switching devices are adapted to be controlled by cams 50 suitably secured to a shaft 51, rotatable in bearings 52 in the supporting frame 53. The supporting frame 53 is formed from suitable metal shapes. The shaft 51 is connected to the elevator machine in such manner as to have a corresponding position to the elevator cab at all times. One revolution of the shaft 51 indicates a complete travel of the elevator between its limits.

There is one cam 50 for each of the switching devices 54. There are two cams with associated switches 54 for each intermediate floor landing and one cam and associated switch for each terminal floor. The periphery of each of the cams 50 is divided into four cam surfaces, the largest diameter 55 being assigned to place the associated switch 54 in the normal position shown in Fig. 2 before the elevator reaches the floor, whether traveling in an up or down direction. The next cam surface 56 permits the operating lever of the switch to move a certain extent, which movement occurs just before the associated floor is reached, and is effective to prepare certain control circuits. The next segment of the cam 57 corresponds to the position of the elevator at the floor and brings it to a stop. The remaining segment 58, shown in the dotted lines, indicates the last position of the elevator when it is travelling past the associated floor to its terminal. The full line of the cam, concentric with the cam surface 58, shows the construction of the cam assigned to one of the terminal floors.

The cams 50 are adapted to operate the switch 54. The switch 54 is mounted on the supporting structure 53 and is provided with a lever arm 59 carrying a roller 60 in a slot 61 and adapted to bear against the periphery of the cam 50.

The lever arm 59 is suitably pivoted in a bracket 62 affixed in any desired manner to an insulating base 63. The insulating base 63 is supported in an angle iron frame 64 and suitably secured thereto.

The bracket 62 is adapted to form a seat for a compression spring 65 that fits against an extension 66 of the lever 59. The lever 59 is held in suitable position by being pivoted at 67 in the upstanding legs of the bracket 62. A connecting link 68 is pivotally secured to the other end of the lever arm 59 and serves to connect the lever arm 59 to the operating member 69 of the switch 54.

The operating member 69 is pivoted at 70 on a bracket 71 suitably secured to the base 63. The operating member 69 is of generally angular shape and is provided with an extension 72. This extension has a small projecting bracket 73 formed integral therewith carrying an insulating roller 74 rotatably mounted therein. The operating member 69 is provided with a further extension 75 that provides a seat for a compression spring 76 that presses against an extension 77 of an operating member 78 that is pivoted on the operating member 69 at 79. An extension of the operating member 78 carries suitable contact making members 80 and 81. The contact making members 80 and 81 are removably secured to the operating member 78 in any desired manner and are preferably made from carbon or other suitable material.

Connecting leads 82 and 83 are employed to make electrical connections to terminals 84 and 85, suitably secured in the base 63.

The contact making members 80 and 81 are adapted to be normally in engagement with contact members 86 and 87, suitably secured to the base 63. The detailed construction of the contact members is shown in Figs. 5 and 6.

The contact member proper comprises a carbon, cylindrically-shaped contact 88, resiliently held in a metal cup 89 against a compression spring 90 by a pin 91 fitting into slots 92 in the metal cup 89. The pin 91 penetrates the contact 88 and constitutes a terminal or a flexible electrical connection 93, the other end of which is secured to an extension 94 of the cup 89. A bolt or stud 95 is threaded into the cup or holder 89 and is provided with threads 96 at its lower end. The bolt 95 is adapted to penetrate an opening 97 in the base 63, and to be firmly fixed thereto by a nut 98. The stud or bolt 95 constitutes the electrical terminal of the contact member.

All contact members are constructed alike. A contact member 99, of the same construction as that described, is removably mounted on the base plate 63 in a position adjacent the operating cam 50 and is adapted to be engaged by a contact making member 100 that is pivoted at 101 on a bracket 102 suitably affixed to the base plate 63. A compression spring 103 serves to maintain the contact making member 100 out of engagement with the contact member 99. The contact making member 100 is provided with an extension 104 to which is rotatably secured an insulating roller 105 adapted to engage the extension 72 of the operating arm 69. The roller 74 of the operating arm 69 is adapted to engage a contact making member 106 that is pivoted at the point 107 on a bracket 108 suitably affixed to the base 63 by a bolt 109 which constitutes the electrical terminal of the contact making member 106. The contact making member 106 is provided with two contacts 110 and 111 which are adapted to engage contact members 112 and 113 respectively. The contact members 112 and 113 are of the same construction as described, and are suitably mounted upon the base 63. A compression spring 114 serves to bring the contact 111 into engagement with the contact member 113. The contact making member 106 is adapted to be operated through the medium of the roller 74 to bring the contact 110 into engagement with the contact member 112. The electrical connections to the various contact making members and contact members are adapted to be made from the bottom of the base through the projecting mounting bolts or contact studs, in an obvious manner.

Having described the mechanical construction of my improved floor selector, I shall now explain its operation.

During the movement of the elevator car, before it reaches the floor associated with cam 50, the roller 60 is riding either about the segment 55 of the cam 50 which has the largest diameter, or that segment 58 which has the smallest diameter. If it is riding about the surface having the largest diameter, the associated switch 54 is effective to bring about the stopping of the elevator at the associated floor. If it is riding about the segment 58, having the smallest diameter, the associated switch 54 is effective to prepare certain registering circuits, the stopping of the car being brought about by another switch 54 associated with that floor. In the first position of the cam, 50, the contacts of the switch 54 are in the position shown in Fig. 2. In the second instance, the roller 60 is riding in the segment 58 and only the contact making member 106 is operated to bring

the contact 110 into engagement with the contact member 112.

Let us assume that the switch 54 of Fig. 2 is going to bring about the stopping of the elevator 5 at the floor with which it is associated. In this instance the roller 60 is riding about the segment of the cam 50 which has the largest diameter. As the elevator car approaches the floor, and about a foot before it reaches it, the roller 60 10 rides into the lower portion of the cam surface 56, thereby permitting the lever 59 to move downwards under the influence of the compression spring 65. The link 68 is thus shifted upwards and the operating arm 69 is rotated about its 15 pivot 70 so that the extension 72 is brought into contact with the roller 105. Further movement of the extension 72 is required to bring the contact making member 100 into engagement with the contact member 99. By reason of the spring connection 96, the operating arm 78 still maintains 20 the contact making members 80 and 81 in engagement with the contact making members 86 and 87. In this position of the switch 54, a circuit is made up for stopping the elevator car. 25 When the floor is reached, the roller 60 falls lower in the cam 50, in engagement with the segment 57, thereby bringing about further turning movement of the lever 59 about its pivot 67, causing the operating member 69 to rotate about its 30 pivot and bring the contact making member 100 into engagement with the contact member 99. The movement of the operating member 69 is sufficient in this instance, however, to ride beyond the roller 105, permitting the contacts 100 and 99 to open and bringing the roller 74 into 35 engagement with the contact arm 106, and also opening the contacts 111 and 113. The contacts 110 and 112 are not yet closed, further movement of the operating arm 69 being required. The 40 movement of the operating arm 69 permits the movement of the operating arm 78 under influence of the spring 96, thereby disengaging the contact making members 80 and 81 from the contact members 86 and 87.

45 The operation of the switch just described, is employed to bring the elevator car to a stop. On further movement of the car past the associated floor, the roller 60 rides in the surface 58 of the cam 50 and the lever 59 brings about further movement of the operating member 69, forcing the roller 74 against the arm 106 to bring the contacts 110 and 112 into engagement. This 50 may prepare a circuit for registering the call from the associated floor. At the terminal floors 55 the associated cams 50 do not have to be formed with the cam section 58, since the elevator does not travel past the terminal floors in either direction. The contacts of the switches 54 do not return to normal position until the elevator has reversed its travel and is in position before the 60 floor associated with the switch 54.

It will be seen that my improved switching mechanism is particularly adapted for the controlling of a plurality of circuits in a simple and reliable manner.

65 While I have described this operation in connection with an elevator system, it will be obvious that it may be adapted to any electrical control system and will do away with a large number of switches and reduce the amount of 70 control equipment required.

Figs. 3 and 4 illustrate my improved selecting device applied to an elevator control system requiring the operation of more circuits, such as 75 would be necessary in a two-speed elevator. The construction and operation of the switch shown

in Figs. 3 and 4 is identically the same as that shown in Figs. 1 and 2, with the exception that the operating arm 72 is provided with another extension 150 carrying contact making members 151 and 152 adapted to engage contact members 153 and 154 mounted upon the base 63. Furthermore, the contact member 100 is provided with an extension 155 carrying a contact member to engage the contact member 156 mounted upon the base 63. These additional contacts are employed to control the two-speed elevator equipment. However, they may be advantageously employed in electrical control systems for controlling other circuits.

80 The angle of the extension 150 may be modified so that the contacts 151 and 154, and 152 and 153 may be opened during any predetermined position of the cam 50. In like manner other contacts and contact making members may be mounted upon the base, as desired, to take 85 care of any number of circuits, and these circuits may be closed at any particular time. Furthermore, a plurality of these switches may be mounted side by side and the cams cut differently to solve any control problem or electrical 90 switching problem that may be encountered. A plurality of these switches 54 may be mounted upon a single slate base in close abutting relation and take but very little space. Similarly 95 associated controlling cams are compactly 100 mounted upon a shaft.

105 While I have described certain specific embodiments of my invention, I am aware that many changes, modifications and deviations may be made without departing from the spirit and 110 scope of my invention, as set forth in the appended claims.

I claim:

115 1. An electric switch comprising a base, a pair of contact members mounted adjacent to one end of said base, a co-operating contact making member associated with each contact member, a bracket mounted on said base adjacent to each of said contact members and adapted to support each of said contact making members, another 120 bracket mounted on said base having an operating arm pivoted thereon, an extension for said operating arm in contact with an extension of one of said contact making members, a roller mounted upon the extension of said operating arm and adapted to contact the other of said contact making members, an operating lever pivoted at one end of the said base and a link connecting said operating lever and member. 125

130 2. An electrical switching mechanism comprising a base, a contact making member and associated contact member mounted on said base, an operating arm for said switch mechanism mounted on one end of said base, an angular shaped operating member pivotally supported on said base and adapted to engage said contact making member, a connection between said angular arm and said pivoted lever, a contact making member mounted on said arm and a cooperating contact member mounted on said base. 135

140 3. An electrical switching mechanism comprising a base, a contact member and associated contact making member mounted at each end of said base, an operating member for operating one of said contact making members, a second operating member for operating the other of said contact making members, and a resilient connection between said operating members. 145

150 4. In an electrical switching mechanism the combination of a base, a contact member and associated contact making member mounted on

- said base, an operating arm pivotally supported on the base and adapted during one portion of its path of movement in one direction to bring said contact making member into engagement with said contact member and during another portion of its movement to bring about the disengagement of said contact members and a rotatable cam for imparting said movement to said arm.
- 10 5. In an electrical switching mechanism the combination of a base, a contact making member and associated contact member mounted on said base, a pair of contact members and associated contact making members mounted on said base, an operating arm pivotally supported upon said base, means for maintaining one contact making member in engagement with its associated contact member, and means operative as a result of pivotal movement of said operating member to disengage the normally engaged contact members and means operative as a result of further pivotal movement of said operating member to bring the remaining contact members into engagement and a rotatable cam for operating said arm during its movement.
- 15 6. In an electrical switching mechanism the combination of a base, a plurality of switches mounted on said base, an operating arm having a plurality of positions and adapted to selectively operate said switches, a disc-like member mounted adjacent said operating member and adapted to operate it into its positions, said disc-like member having a plurality of cam surfaces.
- 20 7. An electrical switch comprising a base, each switch consisting of an independent contact member and associated contact making member, a plurality of switches mounted on said base, an operating arm pivotally mounted on said base for operating said switches, a member pivoted at one end of said base, a link connecting said members and a cam adjacent the last mentioned member and operative to move it into a plurality of positions.
- 25 8. An electrical switching mechanism comprising a base, a contact member and associated contact making member mounted at each end of said base, an operating member for operating one of said contact making members, a second operating member for operating the other of said contact making members, a resilient connection between said operating members, and cam means for operating said operating members.
- 30 9. An electrical switching mechanism comprising a base, a contact member and associated contact making member mounted at each end of said base, an operating member for operating one of said contact making members, a second operating member for operating the other of said contact making members, a resilient connection between said operating members, cam means for operating said operating members and a pivoted operating lever for bringing about the operation of said operating members.
- 35 10. An electrical switching mechanism comprising a base, a contact member and associated contact making member mounted at each end of said base, an operating member for operating one of said contact making members, a second operating member for operating the other of said contact making members, a resilient connection between said operating members, cam means for operating said operating members, a pivoted operating lever for bringing about the operation of said operating members and cam means for operating said lever.
